UNITED STATES PATENT OFFICE.

LUCIUS PAIGE, OF CAVENDISH, VERMONT.

WATER-GAGE FOR STEAM-BOILERS.

Specification of Letters Patent No. 15,617, dated August 26, 1856.

To all whom it may concern:

Be it known that I, LUCIUS PAIGE, of Cavendish, in the county of Windsor and State of Vermont, have invented an Improved Water-Gage for Steam-Boilers; and I do hereby declare that the same is fully described and represented in the following specification and the accompanying drawings, of which—

10 Figure 1, is a front elevation of the same as it appears when its curved slide is opened or is within the niche or recess to be herein-after described. Fig. 2, is a horizontal section taken under such circumstances. Fig. 15 3, is another horizontal section, exhibiting the curved slide as turned around so as to cover the niche. Fig. 4, is a vertical, central and longitudinal section of the said water gage and a portion of the boiler to 20 which it may be applied.

In these drawings A, exhibits the tubular gage having combined with it a separate chamber or vessel B, connected with it and the boiler in such manner, that water and 25 steam from the water and steam spaces of the boiler may flow into the said auxiliary chamber and from thence into the gage.

C, denotes the boiler; while D, and E are 30 pipes leading, from thence into the upper and lower parts of the auxiliary chamber; the pipes by which said gage and the chamber are connected being shown at F, and G, each being provided with a stop cock, a, or, b.

35 The object of the auxiliary chamber is to overcome a difficulty which is incident to the ordinary glass tube gage when such is directly connected at both of its ends with the boiler by means of pipes respectively 40 provided with stopcocks. It is well known, that with a water gage of such construction, it often becomes difficult to determine the actual height of the water in the boiler not only on account of ebullition that is likely

45 to take place in the glass tube, but more especially by reason of foaming water in the boiler, incrustation and other causes well known to engineers. The purpose of the auxiliary chamber is to diminish such causes 50 of disturbance of the proper operations of the tube, and its method of action in order to effect such, may be considered to be well known to engineers. In applying such auxiliary air chamber to the gage A, I extend 55 it partially around the same so as to form about said gage a niche or space H, which I

generally make semicircular or thereabout in horizontal section, and I apply to it and the gage, a cover, I, so adapted to said niche, that when closed, it may extend entirely 60 around the foot of the gage, and with the niche inclose such gage in a heating chamber or space entirely encompassing the gage. The said cover may be constructed of two annular plates, c, c, united together 65 by a plate d bent in the shape of a semi-circle in cross section and with respect to the inner surface of the niche or so as to fit into the same as shown in Fig. 3. In applying the cover to the gage its annular plates, 70 c, c, may respectively encompass and rotate on the metallic heads, f, g, of the gage. Making the inclosing chamber, B, in manner as set forth and providing it with a cover or movable part in manner as de- 75 scribed enabling us to uncover the gage so as to see its contents whenever it may be desirable to do so—as at other times, the gage may be kept entirely covered, such be- 80 ing of service in protecting it from injury, 85 as well as for other purposes.

I do not make the body part of the gage of one single tube of glass, but construct the same of a series of such tubes or sections as shown at, h, h, and with connection rings, 85 i, i, placed between them or arranged as shown in Figs. 1, and 4,—each of said rings being formed with seats or annular recesses x, x, (in their upper and under sides) for the reception of the ends of the glass sec- 90 tional tube or tubes, when applied to the rings as shown in the drawings. And instead of making but one series of said tubes arranged with their axes in a straight line with one another, I construct the gage with 95 two series of glass tubes as shown at h h h, and h', h', h', every tube of one series being made to encircle one of the tubes of the other series.

The objects I have had in view in so con- 100 structing a gage, may thus be stated. In case one of the tubes of the inner series should become broken the tube surrounding it will prevent the escape of steam and enable the gage to be continued in use until 105 a more convenient opportunity to repair it shall occur. Furthermore should any one of the tubes of the external set become broken, the inner tube thereof will sustain the column of tubes and enable the gage to 110 be continued in use. Furthermore, by making the gage of several separate glass tubes

instead of one long glass tube, there is not much danger of its being broken, or getting out of order in consequence of contraction and expansion while its temperature varies 5 from time to time when the gage is in use.

The gage is supported in position by projections, *k*, *k*, extending from the auxiliary chamber or niche such with said chamber constituting a frame for supporting the 10 gage and enabling its lower head or cap *g*, to be forced upward by the action of a screw, *l*, working in a female screw, *m*, the whole being arranged as shown in Fig. 4.

By forcing the caps rings and glass tubes 15 close together their joints will be rendered steam and water tight, particularly if white lead or other suitable cement be first placed between them.

By inclosing the glass gage with a niche 20 as described, the heat radiated from the sides or inner surface of the niche may be employed to gradually increase the temperature of the gage prior to the water and steam being suffered to enter the same. It 25 is well known, that the glass tubes of gages are most liable to become cracked or injured when hot water or steam is suffered to flow suddenly into them, and particularly when they are in a cool state.

30 By my improvement it will be seen that the gage may be warmed or heated, prior to being made to receive the contents of the boiler. This may be done, when the niche is open, although it may be accomplished 35 to much better advantage after the cover of

the niche has been drawn around in front of the glass gage and so as to close up the niche. For the purpose of cleansing the gage or of discharging from it any sediment or matters which may be deposited 40 therein, I provide with a blow cock *m'*, the lower tube by which it is connected with the auxiliary chamber.

I do not herein claim combining with the gage A, a separate receiving chamber, B, 45 arranged between it and the boiler and connected to both, by pipes, but

What I do claim is—

1. Applying the said chamber, B, or arranging it with respect to the gage so that 50 it shall partially surround the same and form a niche or recess, H, to receive such gage and radiate heat upon it toward its axis for the purpose hereinbefore specified, the said recess, H, being provided or not, 55 as the case may require, with the curved cover or slider I, made to operate therewith substantially as set forth.

2. I also claim constructing the gage in tubular sections of glass or other suitable 60 transparent material in combination with providing the same with a clamp frame or apparatus, and connection rings and caps substantially as described.

In testimony whereof I have hereunto set 65 my signature.

LUCIUS PAIGE.
